UNITED STATES PATENT OFFICE.

ALVIN CARR McCORD, OF CHICAGO, ILLINOIS.

DRAFT-RIGGING FOR CARS.

SPECIFICATION forming part of Letters Patent No. 763,998, dated July 5, 1904.

Application filed February 23, 1904. Serial No. 194,625. (No model.)

To all whom it may concern:

Be it known that I, ALVIN CARR McCORD, a citizen of the United States, residing at Chicago, in the county of Cook and State of Illinois, have invented certain new and useful Improvements in Draft-Rigging for Cars; and I do hereby declare the following to be a full, clear, and exact description of the invention, such as will enable others skilled in the art to 50 which it appertains to make and use the same.

My present invention has for its especial object to provide an improved draft-rigging for railway-cars and similar apparatus, but relates, broadly, to improved means for cushioning the movements of relatively movable members.

In the construction of draft-rigging for cars it has hitherto been customary to connect the draft-bar of the coupler to the car-body 20 through the intervention of one or more springs directly applied between the draft-bar and some stationary member of the car-body. In practice it has been found that the maximum movement from normal position which 25 can be advantageously allowed to the draft-bar is approximately two inches. Hence a spring or springs when applied in this manner must be strong enough to directly resist the most intense draft and bumping strains 30 under a compression of two inches or less, or, in other words, under a compression not in excess of the draft-bar movement. As is evident, a spring or springs of such strength will have but very little elasticity under comparatively light strains and will afford an efficient 35 cushion only to comparatively heavy strains or impacts. Furthermore, even under heavy blows or impacts a perfect cushioning action is not afforded because of the considerable 40 force required to impart an initial movement to the spring or springs.

In my pending application, Serial No. 93,403, filed February 10, 1902, entitled "Draft-rigging," I show and claim a construction wherein 45 a multiplying-lever is interposed between the draft-bar of the coupling and the cushioning-spring in such manner that the spring will be given a compressing movement which is materially greater than the movement given to 50 the draft-bar, thus increasing the cushioning

power of the spring and permitting the use of a lighter spring than could be used under the old arrangement wherein the force was applied directly to the spring. In that construction, however, the spring-compressing force is 55 transmitted through the interposed multiplying-lever under a fixed and unchanging ratio or multiplied leverage. Otherwise stated, with the arrangement shown in the drawings of said prior application the cushioning- 60 spring is compressed under a decreased leverage and increased movement relative to the movement of the draft-bar of approximately three to one, so that the cushioning power of the spring is multiplied about three times. 65 In my present invention I go much further than in my said pending application and not only provide means whereby the spring-compressing movement and cushioning power of the spring are increased, but I further provide 70 means whereby the spring-compressing movement and cushioning power of the spring are differentially increased. More specifically stated, in the preferred arrangement of my invention, as illustrated in the drawings of 75 this application, I provide means whereby under movements of the draft-bar from normal position the excess of spring-compressing movement over that of the draft-bar increases from zero and is accelerated until such spring-compressing movement has been multiplied or several times increased over that of the draft-bar, thus correspondingly increasing the cushioning power of the spring. By this arrangement there is afforded a cushion which 80 is extremely sensitive to light blows or impacts and which under heavy blows or impacts first offers a comparatively light resistance thereto and then overcomes the same with a differentially increased or accelerated 85 cushioning power.

In carrying out my present invention in its most approved form I employ differential or variable power-levers, which under spring-compressing and spring-reacting movements 95 have sliding frictional engagement with each other and with coöperating cam lugs or abutments. This sliding and frictional engagement between the differential levers and coöperating parts affords a spring-dampening ac- 100

tion which retards somewhat the action of the springs and prevents sudden recoil of the spring or backlash thereof. By preventing sudden recoil or backlash of the springs of the several draft-riggings of a train surging of the cars is obviated.

The above remarks made with respect to draft-riggings will apply with equal force to a great many other of the many possible applications of my invention to cushioning devices.

My invention is illustrated in the accompanying drawings, wherein like characters indicate like parts throughout the several views.

15 Figure 1 is a view, partly in plan and partly in horizontal section, showing my invention incorporated in a draft-rigging, some parts being broken away. Fig. 2 is a view partly in side elevation and partly in section on the line $x^2 x^2$ of Fig. 1, some parts being broken away. Fig. 3 is a vertical section on the line $x^3 x^3$ of Fig. 1, some parts being removed. Fig. 4 is a horizontal section on the line $x^4 x^4$ of Fig. 2, some parts being left in full plan view. Fig. 5 is a transverse vertical section through the draft-rigging on the line $x^5 x^5$ of Fig. 3. Fig. 6 is a transverse vertical section on the irregular line $x^6 x^6$ of Fig. 3; and Figs. 7 and 8 are views corresponding to Fig. 3, but 30 illustrating different positions of the parts.

The coupler draft-bar 1, only a portion of which is shown, is provided with the ordinary yoke or stirrup 2. As shown, spacing-blocks 3 are interposed between the prongs of the yoke 2 and the rectangular inner end head of the draft-bar, heavy rivets 4 being passed through the said parts to rigidly unite them. Also, as shown, a reinforcing-bar 5 is riveted to the vertically-extended inner end portion 40 of the yoke 2. In the illustration given the draft-lugs or follower-abutments 6 are formed on draft-plates 7, which in turn are rigidly secured to the draft-timbers 8 by means of bolts 9. Followers 10 coöperate with the 45 draft-lugs 6 and are guided in the usual way by flanges of the draft-plates 7. The yoke 2 embraces the intermediate portions of the followers 10 and of course works between the draft-plates 7. The front or forward follower 50 10 is provided with a supplemental section in the form of a casing 11, having at its left-hand extremity projecting angular flanges 12, that embrace the said follower. These flanges 12 normally bear directly against the abutting 55 end or head of the draft-bar 1, and, further, they serve to cause the said follower and its supplemental section 11 to travel together under bumping strains. At its sides the casting or supplemental follower 11 is formed 60 with vertically and longitudinally extended pockets 13 and with detachable plates 14, the latter of which are held in place by short nutted bolts 15. The plates 14 when removed open up the sides of the pockets 13. Within 65 each pocket 13 are several (as shown two) so-

called "differential" power-transmission levers 16 17, which are held in frictional contact with each other. The levers 16 are pivoted at their upper ends and the levers 17 are pivoted at their lower ends. All four of the said 70 levers at their pivot-points are formed with hub-like projections 18, that fit seats formed in part in the shell 11 and in part in the detachable plates 14. The casing 11 and the plates 14 afford a lever carrier or support for 75 the differential levers 16 17. As is evident, the levers 16 17 may be readily removed when the plates 14 are removed, but are securely held in working positions when the said plates are clamped in working positions. The rear 80 follower 10 near its ends is provided with thrust-lugs or lever-abutments 19, that project into the pockets 13 and press against the outer edges of the corresponding levers 16.

Working loosely and telescopically within 85 the casing 11 is a so-called "secondary" follower 20, which, as shown, is approximately cylindrical in form, and at its outer end is formed with a head 20^a, that normally bears against the rear follower 10. This secondary 90 follower 20, as will hereinafter appear, is adapted to move with respect to and out of engagement with said rear follower 10.

A strong coiled cushioning-spring 21, made up of concentric coils, as shown, is located 95 within the housing afforded by the shell 11 and secondary follower 20 and is compressed directly between the front follower 10 and the head 20^a of the said secondary follower 20. The tension of the spring 21 tends to 100 hold the parts in the normal relative positions. (Shown in Figs. 1, 2, 3, and 4.) As shown, the front follower 10 is provided with a rearwardly-projecting stud 22, and the head of the supplemental follower 20 is provided 105 with a centrally-projecting hub 23, which parts 22 and 23 coöperate to hold the spring 21 in position and to prevent the coils of the spring from being jammed together under extreme movements of the followers toward 110 each other. At its inner end the secondary follower 20 is formed with laterally-projecting lever abutments or lugs 24, that work through longitudinally-extended passages 25 and 26, formed, respectively, in the sides of 115 the shell 11 and in the detachable plates 14. These abutments 24 directly engage with the differential levers 17, as best shown in Figs. 3, 7, and 8; but note also Figs. 4 and 5. In Figs. 3, 7, and 8 the heavy dotted lines marked 120 6^a indicate the relative positions of the operative faces of the draft-lugs or follower-abutments 6.

Operation: As already stated, the parts of the draft-rigging normally stand as indicated in Figs. 1, 2, 3, and 4. By reference to Fig. 2 it will be noted that the head of the secondary follower 20 is normally pressed against the rear end follower 10, and by reference to Fig. 3 it will be noted that the abut- 125

ments 24 are normally pressed against the rear end extremities of the slots 25 and 26. Again, by reference to Fig. 3 it will be seen that normally the points of contact between the differential levers 16 17, between the differential levers 16 and the abutments or lugs 19, and between the differential levers 17 and the abutments 24 are in a horizontal plane midway between the fulcrums 18 of the said levers 16 17, so that at this time the said differential levers serve to transmit the strains applied thereto to the cushioning-spring 21 as if directly applied to the said spring by a movement of one of the primary followers 10. The initial movement of one of the said followers 10 acting on the differential levers will, however, immediately change these conditions, as will be observed by reference to Figs. 7 and 8. Fig. 7 illustrates the position of the parts when the rear follower 10 has been given a forward movement under a draft strain which has caused the abutments 19 to engage the differential levers 16 at points higher up than in Fig. 3, so that the effective leverage or spring-compressing force transmitted through the said levers 16 has been reduced about one-half and the movement then being transmitted through the said levers has been about doubled. The obvious effect of this decreased leverage and increased or accelerated spring-compressing movement, transmitted through the levers 17 to the abutments 24, is to cause the secondary follower 20 to move away from and in advance of the rear follower 10. This movement is clearly illustrated in Fig. 7, and by reference to said view it will be further noted that the abutments 24 have moved forward from the rear extremities of the slots 25 26 equal to the distance which said rear follower 10 has moved away from the operative faces 6^a of the rear-follower abutments 6 plus the distance which the rear end of the secondary follower 20 has moved away from the said rear follower 10. Under the movements above noted the forward follower 10 and the lever-support afforded by the casing 11 and plates 14 remain stationary. It is of course evident that under the above-noted movement of the levers 16 17 a gradually-accelerated or differential movement is transmitted to the secondary follower 20 and to the spring 21 and, furthermore, that the said levers can move one upon the other and upon their cooperating abutments 19 and 24 only by a sliding frictional contact, such as will afford the spring dampening or retarding action. Again, it is evident that under the above-noted movements of the parts, imparted thereto by draft strains, the cushioning-spring 21 was compressed by a movement imparted thereto only at its rear end. Fig. 8 illustrates the relative positions of the parts when the draft-bar, under a bumping strain, has been given a rearward movement equal to the forward move- ment imparted to the draft-bar when moved forward, as illustrated in Fig. 7. Under such rearward movement of the draft-bar the rear follower 10 remains stationary—that is, in contact with the rear-follower abutment 6—70 while the forward follower 10 and the lever-support 11 14 are moved rearward. Under this rearward movement of the said parts 10, 11, and 14 the lever-fulcrums 18 are moved rearward, and the differential levers 16 17 are 75 rocked with respect to their coöperating abutments 19 and 24, substantially as before described in connection with Fig. 7. Such movements of the differential levers 16 17 in all cases causes the abutments 24 to move forward and assume a position a greater distance from the abutments 19. Hence even under rearward movements of the draft-bar the rear end of the secondary follower 20 moves forward and away from the rear follower 10. 80 This being the case, it follows that under bumping strains the cushioning-spring 21 is compressed by movements imparted thereto at both ends. However, the amount of compression given to the spring under a given 85 movement of the draft-bar is the same regardless of the direction in which the said draft bar is moved. That this is so will be observed by noting that in Fig. 8 the abutments 24 have separated from the inner extremities of 90 the slots 25 26 the same distance as in Fig. 7 and that this distance is equal to the distance which the follower-flanges 12 have moved from the operative faces 6^a of the forward draft-lugs 6 plus the distance which 95 the rear end of the secondary follower 20 has moved away from the rear follower 10. Figs. 7 and 8 illustrate positions which the various movable parts assume when the draft-bar is moved approximately one-half its possible maximum distance from its normal position, and under such movements the differential spring-compressing movement is produced almost entirely by the shifting points of contact between the abutments 19 and the 100 levers 16. Under further movements from normal position of the draft-bar in either direction, however, the differential levers 17 will be moved into positions in which they will coöperate with said lever 16 to further increase or accelerate the spring-compressing movement transmitted therethrough. Hence it will be seen that while a differentially increasing or accelerated spring-compressing movement is possible with a single differential lever or with a single pair of differential levers nevertheless a plurality of such differential levers or a plurality of pairs thereof is important. The said differential levers may of course be disposed in a great many 115 different ways. By placing them in pairs on the opposite sides of the cushioning-spring 120 the distance between the followers is reduced to a minimum and need be no greater than in the standard draft-rigging, wherein the said 125 130

followers are made to act directly upon the spring. Furthermore, the levers placed on opposite sides of the spring and equal distances on the opposite sides of the axis of the draft-bar the tendency of the telescoping parts of the draft-rigging to buckle sidewise under draft and bumping strains is eliminated. The differential levers, it will be observed, are interposed between one of the primary followers and a so-called "secondary" follower—to wit, as illustrated, between the rear follower 10 and its secondary follower or supplemental section 11. This is one extremely efficient way of arranging the parts, so that under normal conditions a differentially-increasing spring-compressing movement will be imparted to the cushioning-spring through said levers, but in case of disablement of said levers or removal thereof the spring-compressing force will be transmitted directly to the spring, the same as in standard draft-rigging construction.

The cushioning-spring illustrated is treated as a single spring, although, as shown, it is made up of several concentric coils. It might, however, be made up of a single coil or it might be made up of a plurality of coils otherwise disposed. In fact, the so-called "cushioning-spring" might take any desirable form 30 and from a broad point of view might be any suitable resilient device.

From what has been said it will therefore be understood that this invention is generic in its character, and hence capable of a very large range of modification in its details of construction and arrangement of parts, as well as in its applications and uses.

What I claim, and desire to secure by Letters Patent of the United States, is as follows:

40 1. The combination with members to be cushioned, of a cushioning-spring, and one or more differential levers operating differentially to increase the cushioning power of said spring, under the strain applied thereto.

45 2. The combination with members to be cushioned, of a cushioning-spring, and one or more differential levers operating differentially to increase the length of the spring-cushioning movement, under the strain applied thereto.

50 3. The combination with members to be cushioned, of a cushioning-spring and one or more differential levers operating differentially both to increase the length of the spring's cushioning movement and to increase its cushioning power, under strains applied thereto.

55 4. The combination with members to be cushioned, of a cushioning-spring and one or more differential levers operating to increase the cushioning power of said spring proportional to the increase of strain applied thereto, substantially as described.

60 5. The combination with members to be cushioned, of a cushioning-spring and several pairs of differential levers operating to in-

crease the cushioning power of said spring, substantially as described.

6. The combination with members to be cushioned, of a cushioning-spring and several differential levers operating to increase the cushioning power of said spring, and so related as to have a sliding frictional contact with each other, under the movements which vary the leverage thereof, thereby affording a spring-dampening action, substantially as described.

7. The combination with members to be cushioned, of a cushioning-spring and one or more differential levers normally operating differentially to increase the cushioning power of the spring, under the strain applied thereto, but with said parts so arranged that upon said lever or levers, becoming disabled, the strain will be transmitted directly to said spring, substantially as described.

8. In a draft-rigging, the combination with follower-abutments, a draft-bar and co-operating followers, of a cushioning-spring and one or more differential levers operating differentially to increase the spring's cushioning power, under movements of said draft-bar in respect to said follower-abutments, substantially as described.

9. In a draft-rigging, the combination with fixed follower-abutments, a draft-bar and co-operating followers, of a spring interposed between said followers, and one or more differential levers interposed between said spring and one of said followers, with the said parts so arranged that the spring-compressing movement will be transmitted through said lever or levers, under normal conditions, but will be transmitted directly from said followers to said spring in case said lever or levers are disabled, substantially as described.

10. The combination with members to be cushioned, of a secondary follower interposed between said members, a cushioning-spring interposed between said secondary follower and one of the said members to be cushioned, and one or more differential levers interposed between said secondary follower and the other of the said members to be cushioned, substantially as described.

11. The combination with members to be cushioned, one thereof having a lever-support, and the other having laterally-spaced lever-abutments, of a secondary follower interposed between the said members to be cushioned, and provided with oppositely-projecting lever-abutments, differential levers fulcrumed to the said lever-support of the one member, and interposed between the said laterally-spaced abutments of the said other member and the abutments of said supplemental follower, and a cushioning-spring interposed between said supplemental follower and the said member having the said lever-support, substantially as described.

12. In a draft-rigging, the combination with

- fixed follower-abutments and coöperating primary followers, one of said followers having a lever-support, and the other of said followers having laterally-spaced lever-abutments, 5 of a secondary follower interposed between said primary followers, and provided with oppositely-projecting lever-abutments, differential levers fulcrumed to the said lever-support, and interposed between the abutments of said 10 secondary follower and the abutments of said abutment-equipped primary follower, a cushioning-spring interposed between said secondary follower and the said primary follower having the said lever-support, and a draft-bar 15 having a yoke embracing the said followers and arranged to act upon one of the primary followers under bumping strains, and on the other primary follower under draft strains, substantially as described. 20 13. The combination with members to be cushioned, of a cushioning-spring and several levers operating to increase the cushioning power of said spring, said levers having sliding frictional contact with coöperating engaging parts, thereby affording a spring-dampen- 25 ing action, substantially as described.
14. The combination with members to be cushioned, of a cushioning-spring and one or more levers operating to increase the cushioning power of said spring, under strains applied 30 thereto, but with said parts so arranged that upon said lever or levers becoming disabled or removed, the strain will be transmitted directly to said spring, substantially as described. 35

In testimony whereof I affix my signature in presence of two witnesses.
